PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

CIRCUIT CONTROLLING APPARATUS

Application filed January 22, 1929. Serial No. 334,345.

My invention relates to circuit controlling apparatus, and has for an object the provision of novel and improved means for operating contacts at relatively low frequencies, such for example, as frequencies of the order of $1\frac{1}{3}$ to 3 cycles per second.

I will describe several forms of apparatus embodying my invention, and will then point out the novel features thereof in claims.

10 In the accompanying drawing, Fig. 1 is a view, partly in vertical section and partly diagrammatic, showing one form of circuit controlling apparatus embodying my invention. Fig. 2 is a diagrammatic view showing a modification of a portion of the apparatus shown in Fig. 1. Fig. 3 is a fragmentary view showing a modification of another portion of the apparatus shown in Fig. 1.

20 Similar reference characters refer to similar parts in each of the views.

Referring first to Fig. 1, the reference character 1 designates a frame supporting character 2^a, 2^b and 2^c, with three tubular members, with their axes vertically disposed. The outside of each of these tubular members is screw-threaded, and each member coacts with a threaded hole in the frame 1, so that the vertical position of each tubular member 30 may be very accurately adjusted by turning the member in the frame.

The reference characters 3^a, 3^b and 3^c designate coiled springs, the upper end of each of which springs is attached to the associated tubular member 2^a, 2^b or 2^c, so that these springs hang in such positions that their axes are vertically disposed. Attached to the lower end of spring 3^a is a plunger 4^a, a weight 6^a, and a movable contact member 7^a. The springs 3^b and 3^c are provided with corresponding plungers, weights, and contact members. Each contact member 7 coacts with a fixed contact member 8 in the manner hereinafter explained. Each weight 6 is preferably adjustable, and for this purpose it may be in the form of a cup adapted to receive lead shot. Each plunger 4 coacts with an associated solenoid 5 in such manner that if the solenoid becomes energized 50 when the associated spring is at rest in its

position of equilibrium, the lower end of the spring will be lifted above its position of equilibrium.

The amount of the stretch of each spring at its equilibrium point determines the frequency of the vibration of the spring along its vertical axis. The complete period of a vibration is equal to

$$2\pi\sqrt{\frac{L}{G}} \text{ sec.}$$

where L is the stretch of the spring and G is the acceleration due to gravity. It is, therefore, very easy to determine just how much any spring should be stretched for a given frequency. Thus for two cycles per second, the stretch should be $2\frac{1}{2}$ inches.

Each solenoid 5 is preferably iron clad except through the center. One terminal of each solenoid is connected with the associated fixed contact member 8 through a resistance 11, and the other terminal is connected with one of the three points 10 of a contact device comprising a movable member 9 which is adapted to engage any one of the points 10. The movable member 9 is connected with one terminal of a relay R, and the other terminal of this relay is connected with one terminal of a battery B. The remaining terminal of battery B is connected with the frame 1. It will be seen, therefore, that any one of the solenoids 5 and the associated contact 7-8 may be included in circuit with relay R and battery B, depending upon the position of the contact member 9. Each contact 7-8 is so adjusted that it is closed when the associated spring is in its position of equilibrium, but is opened immediately after the lower end of the spring is raised above such position.

The operation of the apparatus shown in Fig. 1 is as follows: Assuming that the contact 9 is in the position shown in the drawing, and that the spring 3^a is at rest in its position of equilibrium, solenoid 5^a will be energized, thus drawing the plunger 4^a upwardly and so opening contact 7^a-8^a. This will break the circuit for the solenoid 5^a, and so the plunger 4^a and weight 6^a will pull the assembly down, thereby stretching 100

spring 3^a. Contact 7^a—8^a will again close at or near the equilibrium point, so that solenoid 5^a will again become energized to raise the plunger and weight. It follows that oscillations will soon be set up and maintained, and that the frequency of such oscillations will be determined almost entirely by the mechanical properties of the spring and its attached mass. It should be noted that current flows for almost exactly one-half the time, that is, for the time that contact 7^a—8^a is closed. It follows that relay R is periodically energized and de-energized, the periods of energization and de-energization being almost equal, and the rate of operation of its contact being determined by the frequency of oscillation of the spring 3^a.

If contact member 9 engages with contact point 10^b, the rate of operation of relay R will depend upon the characteristics of the spring 3^b, and its attached mass and if contact member 9 is in engagement with contact point 10^c, the rate of operation of relay R will depend upon the characteristics of spring 3^c and its attached mass.

As an example, the characteristics of the apparatus may be such that the rate of oscillation of spring 3^a is 3 cycles per second, the rate of oscillation of spring 3^b is 2 cycles per second, and the rate of oscillation of spring 3^c is 1 1/3 cycles per second.

Relay R may be used for any suitable purpose. As here shown, it is employed to periodically interrupt the supply of automatic train governing current to the rails of a railway track. These rails are designated 13 and 13^a, and they are divided by insulated joints 14 to provide a track section. Alternating train governing current is supplied to the rails by a generator G, and the circuit includes contact 12 of relay R, so that each time that relay R is energized, alternating current is supplied to the rails, whereas each time relay R is de-energized, the supply is interrupted. The train carried apparatus which responds to the train governing current thus periodically supplied to the rails forms no part of my present invention and is omitted from the disclosure.

Considering now any one of the spring, plunger, and weight assemblies, it will be noted that when oscillations are started, the solenoid 5 is energized while the weight moves from its middle position to its lowest point, as well as when it is rising from its lowest point to its middle position. Thus it would be expected that the assembly would be slowed down while descending as much as it is accelerated while rising, and that no amplitude greater than the first kick would be obtained and no free vibration set up. This is, in fact, the case when the solenoid current at once attains its steady value. This could be guarded against by a system of re-

lays which would energize the solenoid when and only when the plunger is rising, but I have discovered that this complication is unnecessary if the time constant of the energizing circuit is of the same order as the natural period of oscillation of the assembly. This condition is easily realizable in practice for frequencies of the order of one to three cycles per second. Thus if the time constant of the solenoid circuit is equal to the half period of oscillation of the assembly, the average current value for the quarter period during which the assembly is rising is 2.61 times that for the quarter period in which the assembly is moving downward, so that the acceleration while the assembly is rising is much greater than the retardation while descending, with the result that relatively large amplitudes only slightly forced are built up.

It is, however, desirable to limit the amplitude to a convenient amount and at the same time to have a strong starting force with relatively low voltages. I find that this can be accomplished by making the length of the solenoid about the same as the desired amplitude of the motion of the plunger, and adjusting the spring support so that in its equilibrium position with no current in the solenoid, the upper end of the plunger is at a position 40% of the length of the solenoid above the lower edge of the solenoid. The force from this point to the lower end of the solenoid varies from a maximum to zero, so that if the amplitude becomes large, there is no force acting on the plunger for the part of its oscillation during which it is below the lower level of the solenoid, and a smaller force is exerted near the bottom of the solenoid than that exerted at the equilibrium point. This characteristic is useful because it permits a considerable starting force at low voltage and because it limits the amplitude of vibration without artificially increasing the damping. Artificial increase of damping would affect the frequency of oscillation.

The purpose of resistances 11 is to adjust the time constants of the circuits for the solenoids to the order of one-half of the natural period of oscillation of each assembly. In practice this resistance can be wound into the coils 5^a, 5^b and 5^c if desired.

Referring now to Fig. 2, the apparatus is the same as that shown in Fig. 1, except that the solenoid circuits include the primary of a transformer T instead of the winding of a relay R. The secondary of this transformer is connected with the winding 17 of a polarized relay R^p, the contact 12^p of which controls the supply of alternating current to the track rails 13 and 13^a. Each time the primary circuit is closed an impulse of one polarity is supplied to relay R^p, and each time the primary circuit is open an impulse of

the opposite polarity is supplied to this relay. The polarized armature 16 is biased to remain in either position to which it is moved, and so it follows that the operation of contact 12^a is the same as the operation of contact 12 in Fig. 1. The apparatus shown in Fig. 2 will probably require a smaller amount of power than the apparatus shown in Fig. 1.

As stated hereinbefore, the assembly including the spring 3^c may be adjusted to oscillate at a frequency of 1 $\frac{1}{3}$ cycles per second. This requires a spring stretch of about 5 $\frac{1}{2}$ inches. In order to reduce the height of the apparatus, this stretch may be obtained by a cantilever spring instead of a coiled spring. Referring to Fig. 3, the reference character 18^c represents a cantilever spring, the lower end of which is fixed and the upper end of which is connected with the plunger 4^c. In other respects the apparatus shown in Fig. 3 is the same as that portion of Fig. 1 which is associated with the spring 3^c. The modification shown in Fig. 3 provides greater compactness than the form shown in Fig. 1.

One feature of apparatus embodying my invention is that it requires very little power for operation, because the losses in the timing mechanism are very small. Another feature is that the period of oscillation of each assembly is constant to a marked degree, and is independent of temperature and applied voltage, since it is determined by the elastic constants of the spring material and the amount of mass attached to the spring. The variation of the modulus of rigidity upon which spring stiffness depends with temperature, is such as to affect the frequency only about 1% or less for a change in temperature of 180° F.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. Circuit controlling apparatus capable of sustaining self oscillation and accurately adjustable as to frequency, said apparatus comprising a spring one end of which is fixed in a position adjustable as to height and the other end of which is free to move in a substantially vertical line, a plunger attached to the free end of said spring, a weight adjustable in mass attached to the free end of said spring, a flexible contact member having one end fixed, a movable contact member attached to the free end of said spring and engaging the free end of said flexible contact member when the free end of said spring is in its position of equilibrium but not when the spring is raised from such position, and a fixed solenoid controlled by the contact formed by said two contact members and co-

acting with said plunger to raise the free end of said spring from its position of equilibrium, the parts being so proportioned and so adjusted that if said solenoid is energized over the contact formed by said two contact members said spring and weight assembly will oscillate at substantially its natural period.

2. Circuit controlling apparatus capable of sustaining self oscillation, said apparatus comprising a spring one end of which is fixed and the other end of which is free to move in a substantially vertical line, a plunger attached to the free end of said spring, a flexible contact member having one end fixed, a movable contact member attached to the free end of said spring and engaging the free end of said flexible contact member when the free end of said spring is in its position of equilibrium but not when the spring is raised from such position, and a fixed solenoid controlled by the contact formed by said two contact members and coacting with said plunger to raise the free end of said spring from its position of equilibrium, the parts being so proportioned that the time constant of said solenoid is of the same order as the natural period of said spring and plunger.

3. Circuit controlling apparatus capable of sustaining self oscillation and accurately adjustable as to frequency, said apparatus comprising a spring one end of which is fixed in a position adjustable as to height and the other end of which is free to move in substantially a vertical line, a plunger attached to the free end of said spring, a weight adjustable in mass attached to the free end of said spring, a flexible contact member having one end fixed, a movable contact member attached to the free end of said spring and engaging the free end of said flexible contact member when the free end of said spring is in its position of equilibrium but not when the spring is raised from such position, and a fixed solenoid controlled by the contact formed by said two contact members and coacting with said plunger to raise the free end of said spring from its position of equilibrium, the length of said solenoid being approximately the same as the desired amplitude of motion of said plunger and the parts being so adjusted and so arranged that when the free end of said spring is in its position of equilibrium the upper end of said plunger will be at a position approximately 40% of the length of the solenoid above the lower edge of the solenoid, whereby the amplitude of motion of the plunger is limited without artificially increasing the damping of the moving parts.

In testimony whereof I affix my signature.
PAUL N. BOSSART.
